UNITED STATES PATENT OFFICE

GEORGE M. SHOBER, OF OTTUMWA, IOWA

CRANKLESS ENGINE

Application filed November 12, 1931. Serial No. 574,541.

My invention relates to crankless engines, one of its objects being the provision of an engine in which the usual crank shaft is omitted, the drive shaft being driven through rocking mechanism which is actuated by the movement of the pistons of the engine.

Another object of the invention is the provision of novel mechanism for converting the reciprocatory movements of the pistons into rotary motion.

Having in view these objects and others which will be pointed out in the following description, I will now refer to the drawings, in which

Figure 1 is a vertical sectional view of the mechanism for converting reciprocating motion into rotary motion.

Figure 2 is a view of the mechanism shown in Figure 1 as it appears when looking at the rocking spider and in the direction of the under side of the cylinders.

Figure 3 is a perspective view of the rocking spider.

Figure 4 is a view in perspective of the connecting member between the rocking spider and the fly-wheel of the engine.

Figure 5 is a perspective view of the universal joint in the drive shaft of the engine.

Figure 6 is a diagrammatic view showing the valve actuating mechanism.

Figure 7 is a view in median vertical section showing particularly the valve actuating mechanism.

Figure 8 is a view in elevation showing one of the rocker arms.

Figure 9 is a view in elevation showing the rocker arm support.

Referring now particularly to Figures 1 and 2, it will be seen that there are shown four cylinders 10 with pistons 11. These cylinders are preferably arranged at equal distances from a common center. While I have shown the engine with four cylinders, it is obvious that the number may be increased, it being only necessary that there be an even number of cylinders. The cylinders are surrounded by a casing 12 which provides with the cylinders 10 a water jacket surrounding the cylinders and designed for cooling

the engine. The cylinders 10 are arranged in pairs so that when two of the pistons are in their extreme downward position the other two pistons will be in their extreme upward position. Each piston 11 is provided with a piston stem 14.

Depending from the casing are two supports 15. The spider 16 shown in Figure 3 is provided with two pins 17 integral therewith and adapted to be journaled in the supports 15. The spider is thus adapted to be rocked about the axis passing through the two pins 17. The spider is also provided with four pins 18 for engagement through the apertures at the lower ends of the piston rods 14. The movements of the pistons 11 will thus be communicated through the piston rods 14 to rock the spider 16 about its fixed axis.

At the bottom of the casing 12 is a flywheel 19 which is rotatable within the casing. Secured to the flywheel and integral therewith is the shaft 20, this shaft being journaled in the sleeve 21 which is integral with the bottom of the casing. Secured to the sleeve 21 at its upper extremity is a pinion 22 which is rigid in position relative to the casing. The upper portion of the flywheel is provided with an upwardly and outwardly inclined ear 23 in which is journaled a shaft 24. The gear 25 is secured to the shaft 24 at the lower extremity thereof. The connecting member 26 has coaxial bearing parts 27 for receiving the shaft 24. It also has a pair of ears 28 with bearing collars adapted to receive the pins 29 of the rocking spider. The connecting member 26 is therefore rocked through the movements of the rocking spider but its lower extremity is compelled to follow a fixed circular path about the axis of the shaft 20.

The shaft 24 is rotatable in the bearings 23 and 27 and it also has limited sliding movement in these bearings. As the speed of the engine increases the end thrust on the shaft 24 decreases and the gear 25 consequently moves to a slightly higher level. The shaft 24 terminates at its upper extremity in a universal joint connection 30 with the shaft 31. The axis of the universal joint 30 is

within the plane of the rocking spider 16.

The shaft 20 is the power take-off shaft. For this purpose it may be provided with a pulley or with a helical or other gear of any

5 suitable kind for transmitting the power from the shaft 20. The shaft 31 is within the space between the four cylinders and it is to be used in my engine for controlling all of the timing mechanisms such as the spark 10 plugs and the valves of the engine.

In the space between the four cylinders is a frame 32 supporting the valve actuating mechanism. The shaft 31 as shown in Figure 7 has an upward and outward inclination 15 and it terminates in a bevel pinion 33. This pinion cooperates with a gear on the inner or under side of a cup-shaped disc 34 which is rotatably secured to the support 32 by means of the spindle 35. Projecting upwardly from the disc 34 are cams 36, the 20 number of cams corresponding with the number of cylinders of the engine. These cams 36 are positioned at various radial distances from the axis of rotation of the disc 34.

Each cylinder has an exhaust valve 37 and an intake valve 38, the valves 37 and 38 in the four cylinders being arranged as shown in Figure 6. In connection with each pair 30 of exhaust and intake valves there is a rocker arm mechanism for opening these two valves in succession. The mechanism includes a supporting casting 39 which is adapted to be bolted onto the frame of the cylinder.

35 Each casting 39 has two pairs of upwardly projecting ears 40, each pair of ears 40 having a pin connection 41 for supporting a rocker arm as shown in Figure 8. The rocker arm 42 rests on the spring pressed valve stem 43 but at its rear end it carries a roller 44 which lies in the path of a cam 36. When the roller 44 rides over a cam 36, the rear end of the rocker arm 42 will be elevated to depress the outer end of the rocker arm 42 and 40 to thus depress the valve stem 43 and to momentarily open the valve. As soon as the roller 44 has passed the cam 36 the valve stem 43 will be forced upwardly under the action of its spring to thus close the valve. 45 The cams 36 correspond in number with the number of cylinders but they are so arranged with reference to each other and with reference to the rocker arms 42 that they will actuate the valves of the cylinders in succession, the exhaust valves in each case being actuated before the intake valve.

60 The firing system is not illustrated in my drawings since it is optional and since it is well understood by all expert in gas engine design. The drive which I have shown and described is to be used on a single, two cylinder or four cylinder engine. Every other down stroke in a four cycle engine is the power stroke, the other stroke being the intake stroke. The firing order may thus be

either 1-2-4-3 or 1-3-4-2, this being optional since it makes no difference in the operation of the engine. This requires but one cam for each pair of rocker arms.

65 The relative speed of the shaft 31 is governed entirely by the gear ratio of the gears 22 and 25. In my preferred construction I employ a 3 to 1 gear ratio but it is obvious that this ratio may be altered as desired. Since the shaft 31 controls the action 70 of the valves, it is essential that the gears 22 and 25 be proportioned in accordance with the engine design.

75 The above described construction involves in particular two novel features of construction. First, there is the relative arrangement of the cylinders with respect to the flywheel and rotating parts. Second, there is the specific construction and arrangement 80 of the valve operating shaft which derives 85 its turning power from the gear wheel and stationary gear in its peculiar association with the oscillating head.

85 Having thus described my invention in such full, clear, and exact terms that its construction and operation will be readily understood by others skilled in the art to which it pertains, what I claim as new and desire to secure by Letters Patent of the United States is:

1. Means for converting reciprocatory motion into rotary motion including a supporting frame, a reciprocating member supported in said frame, a shaft journaled in said frame, said shaft being parallel to the direction of movement of said reciprocating member, a flywheel secured to said shaft, a rocking spider pivotally secured to said frame and to said reciprocating member, and a connecting member pivotally secured at one of its extremities to said spider at right angles to the pivotal connection between the frame and the spider and having an eccentric bearing at its other extremity with said flywheel. 100

105 2. Means for converting reciprocatory motion into rotary motion including a supporting frame, a reciprocating member supported in said frame, a shaft journaled in said frame, said shaft being parallel to the direction of movement of said reciprocating member, a flywheel secured to said shaft, a rocking spider pivotally secured to said frame and to said reciprocating member, a connecting member pivotally secured at one of its extremities to said spider at right angles to its 110 pivotal connection to the frame and having an eccentric bearing at its other extremity with said flywheel, a second shaft journaled in said connecting member, and a third shaft having a universal joint connection in the plane of the pivotal connection between the frame and the spider with said second shaft and positioned in alignment with said first named shaft. 115

120 3. Means for converting reciprocatory mo-

tion into rotary motion including a supporting frame, a reciprocating member supported in said frame, a shaft journaled in said frame, said shaft being parallel to the direction of movement of said reciprocating member, a flywheel secured to said shaft, a rocking spider pivotally secured to said frame and to said reciprocating member, a connecting member pivotally secured at one of its extremities to said spider at right angles to the pivotal connection of the frame and having an eccentric bearing at its other extremity with said flywheel, a second shaft journaled in said connecting member, a third shaft having a universal joint connection with said second shaft and positioned in alignment with said first named shaft, a stationary pinion secured to said frame, and a gear secured to said second shaft and intermeshing with said pinion.

4. In an engine, pairs of parallel cylinders with pistons therein, a support disposed between the pairs of cylinders and pistons, a spider pivotally mounted in said support on an intermediate axis, connecting means between the opposite ends of the spider and said pistons, a connecting member pivotally mounted upon the opposite ends of the spider on an axis at right angles to the connection of the spider to the support, a fly-wheel having a shaft with its axis intersecting the axis of the spider at the point of intersection of

the spider and the connecting member therewith, a stationary pinion disposed about said shaft, a second shaft disposed co-axially in the connecting member and having a bearing connection with the fly-wheel at one side of said pinion, and a gear-wheel mounted on said second shaft meshing with said pinion adapted to traverse the latter upon rotation of the fly-wheel and turn said second shaft.

5. In an engine, a pair of cylinders, a bracket fixed between the cylinders, a spider pivotally mounted intermediate its ends on said bracket, pistons disposed in the cylinders having rods pivotally connected to the opposite ends of the spider, a connecting member hinged upon the spider on an axis at right angles to the pivotal connection of the spider with the bracket, a shaft disposed between said cylinders, a second shaft mounted co-axially in the connecting member and having a universal connection with the first shaft in the plane of the spider, a fly-wheel having a shaft co-axial with said first shaft and having an eccentric bearing for receiving the adjacent end of the second shaft, a gear on said second shaft in the fly-wheel, and a stationary pinion concentric with the fly-wheel shaft meshing with said gear for turning the latter during rotation of the fly-wheel.

In testimony whereof I affix my signature.

GEORGE M. SHOBER.
